UNITED STATES PATENT OFFICE

WILLIAM E. ROTHERMEL, OF CHICAGO, ILLINOIS

FUEL-SAVING DEVICE

Application filed July 30, 1928. Serial No. 296,174.

This invention relates to improvements in fuel saving devices, and more especially to such a device adapted for attachment to a furnace, heater, stove, boiler, or the like.

5 One of the features of my invention is the provision of a mechanism or contrivance adapted to be fastened to the inside of the feed door so that air entering through openings in the door will pass through the device 10 and also around it in contact with its outer walls, thus becoming preheated so that as it comes in contact and mixes with the gases of the fuel bed combustion will be promoted, such mixing of preheated air with the gases 15 of the fuel bed also reduces the smoke and lessens soot. The increased efficiency in combustion produced by my device naturally results in fuel economy.

My device also operates to insulate the feed 20 door, or other parts of the wall of the combustion chamber, where the device is used, to prevent loss of heat.

Other features and advantages of my invention will appear more fully as I proceed 25 with my specification.

In that form of device embodying the features of my invention shown in the accompanying drawings, Figure 1 is a view in front elevation of a feed door; Fig. 2 is a rear view 30 of the same showing my fuel saving device attached; Fig. 3 is a view similar to Fig. 2 showing the vertical section of the device; Fig. 4 is a view taken as indicated by the line 4 of Fig. 3; and Fig. 5 is a view taken as indicated by the line 5 of Fig. 3.

As shown in the drawings, 10 indicates, in general, any furnace, stove, boiler, heater, or the like, and 11 the feed door for the fuel feed passage in one wall thereof. 12 indicates the butterfly valve air regulator or damper attached to the feed door to regulate the amount of air entering the combustion chamber above the fuel bed.

My improved fuel saving device comprises 45 a substantially rectangular chamber 13 adapted for attachment at the inside of the door in any suitable manner. The chamber 13 is preferably spaced inwardly from the door a short distance to leave the space 14. 50 It may be supported in any suitable manner;

and I have here shown for such purpose the device 13 provided with four supporting bars 15 at the corners, the ends of the same being bent downwardly, as indicated by 15^a and inserted in sockets or eyes 16 mounted on the 55 inside of the door 11.

The outer peripheral walls of the chamber 13, indicated by 13^a, are preferably slanted or tapered inwardly from the outside to the inside, as shown most clearly in Figs. 2, 4 and 60 5. The outer or front face of the chamber 13 is indicated by 13^b and the inner or rear face is indicated by 13^c. The front face 13^b is provided with a centrally arranged opening 17 for the admission of air into the device. 65 Inside of the chamber 13 are arranged baffle-plates 18 around the central opening 17 so that air entering said openings must follow a tortuous passage through the chamber 13 to the outlet openings 19 in the lower edge 70 of the rear or inner face 13^c. Passage of air through the device is indicated by the arrows.

The outlet openings 19 need not necessarily be in the lower edge of the face 13^c. For example, if the level of the fire bed is relatively 75 high these openings may be located correspondingly higher. In fact, they may be placed anywhere in the inner face, though of course it would not be advisable to place them in that portion of the face directly opposite the opening 17 as little or no baffling effect would then be obtained.

It is to be particularly noted that the chamber 13 is spaced inwardly a short distance 80 from the feed door 11 so as to leave the space 14 between. Consequently, some of the air entering through the feed door will not pass into the opening 17, but will be deflected outwardly around the outer walls of the chamber 13 and in contact therewith, as indicated 85 by the arrows, such air coming in contact with the outer walls of the chamber will also be preheated. It is to be understood that the entire chamber is heated both by radiant and sensible heat from the combustion in the combustion chamber, and consequently air passing 90 through the chamber around the baffles 18 will also be preheated before escaping through the openings 19 into the combustion 95 chamber.

The chamber 13 having a double wall and lying inside of the feed door acts as an insulator for the feed door, thus conserving the heat in the combustion chamber. Acting as such insulator for the feed door, the usual feed door insulator lining to protect the same from heat may be dispensed with.

It is to be noted that the chamber 13 is readily removable from the feed door by lifting the ends 15^a of the bars 15 out of the sockets 16. The device may, therefore, be readily removed for cleaning, repairing or replacement.

While I have shown and described certain embodiments of my invention, it is to be understood that it is capable of many modifications. Changes, therefore, in the construction and arrangement may be made without departing from the spirit and scope of the invention as disclosed in the appended claim, in which it is my invention to claim all novelty inherent in my invention as broadly as possible in view of the prior art.

What I claim as new, and desire to secure by Letters Patent, is:

In combination with a fuel-feed passage of a furnace or the like and a door therefor provided with a damper, an air-heating casing, bar means connecting the door and casing and normally disposing the latter in said passage in spaced relation to the door and to the walls of the passage, said casing having its marginal wall inwardly tapering and also having a centrally arranged air inlet opening facing said door, whereby the air passing the damper will partly pass around said marginal wall and will partly enter said opening, and the casing adjacent its inner lower corner having air outlet openings, and baffle means in said casing providing a tortuous passage to be followed by the air in its travel from said inlet means to said outlet means.

In witness whereof, I have hereunto set my hand, this 26th day of July, 1928.

WILLIAM E. ROTHERMEL.
